[Term of Patent 3½ years.]

N.

To all whom it may concern:

Be it known that I, ALFRED HEALD, of the city and county of Philadelphia, State of Pennsylvania, have produced or invented a Design for a Carpet-Pattern, of which the following is a specification:

The principal features of my design are the angular ribbons A, which cross each other in the manner clearly shown by the figure in the accompanying drawing, so as to inclose spaces *a*, *b*, and *c*, the two former of which contain central ornaments *d* and *e*, while the space *c* is shaded and ornamented by a series of small scrolls.

Irrespective of the colors employed, I claim—
The design for a carpet-pattern composed of ribbons A, inclosing ornamented spaces *a*, *b*, and *c*, as described, and represented in and by the accompanying drawing.

In testimony whereof I have signed my name to this specification in the presence of two subscribing witnesses.
